UNITED STATES PATENT OFFICE.

JOHN MARQUIS, OF SAN FRANCISCO, CALIFORNIA, ASSIGNOR TO HIMSELF
AND JOHN J. NEWSOM.

IMPROVEMENT IN WATER-CLOSET REGULATORS.

Specification forming part of Letters Patent No. 147,510, dated February 17, 1874; application filed November 12, 1873.

To all whom it may concern:

Be it known that I, JOHN MARQUIS, of San Francisco, in the county of San Francisco and State of California, have invented an Improved Water-Regulator mainly adapted to Water-Closets; and I do hereby declare that the following is a full and exact description of the same, reference being had to the accompanying drawings and to the letters of reference marked thereon.

The object of my invention is to provide an improved device for regulating and measuring the flow of water employed in water-closets; and it consists of a cylinder of suitable capacity having a closely-fitting piston, and also provided with water-passages leading from either end of the cylinder to a valve-chamber, in which moves a valve so operated as to cause one end and the other of the cylinder to fill alternately. As one end is filling with water the opposite end is being discharged by the pressure through suitable passages into the bowl.

Referring to the accompanying drawings for a more complete explanation of my invention, the figure shows a side sectional elevation of the regulator.

H H' are the spaces above and below the piston, respectively, in a cylinder of such a size as to hold a sufficient quantity of water to thoroughly cleanse the bowl. The piston E is packed, so as to fit and move closely within the cylinder; and this piston is fitted with leather caps or packing b at each end, which serve to close the ports K K' whenever the piston arrives at either end. These ports communicate by a transverse passage with the vertical passages A A', as shown. The passages A A' extend along the side of the cylinder, and terminate just beneath the valve-seat opening into the valve-chamber by means of the ports C C'. B is an induction-port, and F

the eduction-port discharging into the bowl. The valve D may be balanced, rotary, or other suitable form, but I have employed in the present case the ordinary slide-valve with a stem, a, extending up through the upper end of the valve-box, being suitably packed. This rod may be operated by hand, or by a person's weight, as desired, or the valve may have a spring which will keep it forced in one direction, while, by the hand or pressure, it can be moved in the other.

The operation will be as follows: The water entering beneath the valve through the passage B passes through the port C into the passage A, and thence through the opening K into the cylinder above the piston E. The pressure forces the piston to the lower end of the cylinder, driving out the water that had previously entered below, when the valve is moved to its other position. This water passes out through the opening K' and up the passage A', thence through the port C', and out at F into the bowl.

By this arrangement the amount of water used can be regulated, and it will not be possible to tamper with the machine, so as to cause the water to flow all the time.

Having thus described my invention, what I claim, and desire to secure by Letters Patent, is—

The combination of the piston E, constructed as described, with the cylinder having the ports K K', passages A A', ports B and F, and valve, constructed and arranged in relation to each other, as described.

In witness whereof I have hereunto set my hand and seal.

JOHN MARQUIS. [L. s.]
